UNITED STATES PATENT OFFICE

2,502,075

BLOCK MOLDING MACHINE AND PROCESS

Morton Clark, Seattle, and Frank C. Priestly, Edmonds, Wash., assignors to United States Loc-Bloc Corporation, Seattle, Wash., a corporation of Washington

Application September 3, 1946, Serial No. 694,582

13 Claims. (Cl. 25—57)

1

The present invention relates to the molding of concrete blocks, and more especially to the molding of concrete blocks which incorporate ribs projecting from an upper edge and from one upright edge to fit closely within similarly spaced grooves in the lower edge of the blocks in the course next above, and in the abutting upright edge of the adjoining block in the same course, respectively. Such concrete blocks are disclosed in the patent to William A. Wells, No. 1,565,537, dated December 15, 1925. Somewhat similar blocks are disclosed in the patent to Robert D. Wells, No. 2,371,201, dated March 13, 1945.

Ordinarily in the construction of concrete building units some variation in dimensions is permissible, that is to say, the tolerance is fairly wide, for the normal allowance for mortar space can absorb any such variation. With such blocks as are illustrated in either Wells patent, however, which are laid up without mortar, and which interlock by the interfitting ribs and grooves, or lugs and sockets, each block must be of precise dimensions, within a very small tolerance. Otherwise, there will be cracks between adjoining units, and the projecting ribs will not properly fit within the grooves that are intended to receive them, hence the blocks will not lie in straight courses, nor will they mutually support one another, as is intended.

Very considerable difficulty has been encountered heretofore in molding blocks of this type with the necessary degree of precision. The blocks must be produced at a rapid rate, in order that their cost may be kept low, and in so producing them, it has been found difficult to maintain their accuracy within the required tolerance.

We have discovered that the lack of accuracy is not due to a fault in the mold box, nor in the molding process, nor is it due to lack of accuracy in the construction of parts, but it arises from the fact that in the compressing operation a certain part of the air which permeates the entire block is trapped within the block, and is unavoidably compressed therein, with the result that when the pressure is released, preparatory to discharge of the compressed but unset block from the mold box, the air thus compressed tends to expand again, and thus increases the size of, or distorts the block at that point at which the compressed air is first released. Primarily, the difficulty lies with the entrapment of a small residue of air and its compression within the block, followed by first release of the pressure in a small area, giving rise to the distortion of

2

the block in the vicinity of the portion first uncovered.

Accordingly, it is one of the primary objects of the present invention to devise a process, and mechanism for carrying out the same, by means of which expansion of the entrapped and compressed air is so controlled that it will not disturb the ultimate size or shape of the block, but will leave it, when the pressure is fully released, in exactly the intended shape and size.

It is, of course, also an object to provide a practical machine and a method of molding blocks by which such blocks can be molded expeditiously and cheaply, starting with loose concrete mixture and ending in a compressed block of exact and uniform dimensions, which can be carried away for curing.

In such a process as has been sketched immediately above, it becomes necessary to handle the block as it is delivered from the mold box, immediately after it has been compressed, and long before it has acquired any set. Moreover, since the most practical way of discharging such a block from the mold is to open the mold box and permit the block to be delivered by gravity, this has the serious drawback that such an unset but compressed block is likely to be disturbed, particularly in the region of the projecting ribs and the grooves, if it is permitted to drop by even a few thousandths of an inch relative to the die plates by which it is formed. In consequence, one of the additional important objects of the present invention is to provide a process and a machine for carrying out the same, by which such blocks may be contacted very precisely by a pallet or the like, applied to its bottom immediately prior to the opening of the mold box, to the end that the block may be supported in situ until the mold box has opened widely enough to permit the block to clear all parts of the mold box, and only then to strip the mold box parts from the block.

It is an object to provide a machine having a construction and a cycle of operation by which there can be produced single blocks in rapid succession, or which may be converted to the manufacture of blocks in multiples, and which is compact in size and rugged in construction. Moreover, it is an object to devise such a machine which, while rugged, rapid, and efficient in operation, will nevertheless permit operational movement of parts within the accuracy of a few thousandths of an inch in such places and operations where such extreme accuracy is desirable.

With these and other objects in mind, as will appear hereafter, the invention comprises the novel process and the novel machine for molding concrete blocks or like products, as shown in a typical form in the accompanying drawings, as described in the specification, and as will be made clear by the claims which terminate the same.

In the accompanying drawings the machine of the invention is shown in a typical and operative form, but it will be understood that the details thereof, and the detailed arrangement of the parts relative to one another, may be varied within the scope of the appended claims.

Figure 1 is in general a top plan view of the machine, with various parts omitted or broken away, and Figure 2 is in general an end elevation of the same, broken back generally as indicated by the line 2—2 of Figure 1.

Figure 3 is a detail cross section taken on the line 3—3 of Figure 1.

Figure 4 is in general a side elevation, with parts broken back and shown in section.

Figures 5, 6, 7, and 8 are successive diagrammatic showings, illustrating the cycle of operation.

According to the present invention a mold box is made up of a front die plate 1, a rear die plate 2, both of which are shiftable, and a fixed mold cavity liner having end plates 11 and a connecting bottom 14, which rests upon a fixed table 30. A reciprocable yoke 10 carries the front die plate 1. The rear die plate 2 is carried by a yoke 20, which is movable with and also with respect to the front die plate 1. Such a mold box is open at its top, and in its discharging position is open at its bottom, and at its ends. One of the die plates, as, for example, the die plate 1, is formed with ribs 12 which define grooves in the molded block, while the other die plate, as 2, has complementary depressions 22 by which are formed upon the block projecting ribs which are intended to be received in the grooves formed by the ribs 12, in blocks of the course above, when the block is laid up in a wall.

By substituting one liner 11, 14 for another the one mold box can turn out different sizes of block. When the liner is replaced, a different set of die plates 1, 2 must be used, for these dies fit closely the liner 11, 14, and the die plate 2, at least, slides between the end plates 11 and over the bottom 14.

The yoke 10, it will be observed, extends to the opposite end of the machine, and is guided at 13 in the frame 3 for sliding movement in a generally horizontal plane with respect to the frame. The yoke 20 may be considered as carried by and movable with the yoke 10, but it is guided thereon at 23 for such movement relative to the yoke 10 as may be necessary to effect compression approach and then relaxation or recession of the die plates 1 and 2.

The mold box, constituted by the die plates 1 and 2 and the liner 11, 14, is open at its top. It is adapted to be placed in registry in one position with a hopper 4, supported upon the frame and terminating in a position to register with the mold box when the movable parts of the latter have been withdrawn to charging position. During such registry the mold box is filled with loose concrete material in a rather dry mix. The bottom of the mold box is closed at such time by the liner bottom 14, resting upon a table 30, which in effect is a part of the fixed frame. The mold box, or at least the die plates 1 and 2 which constitute an important part thereof, is shiftable

from this charging position outwardly beyond the table 30 and liner 11, 14 to a discharging position, and the ensuing movement of the block, supported only by the die plates 1 and 2, trowels the remaining surfaces as it passes the liner 11, 14. Some means must be provided to close the top of the mold box during compression of the charge, and to prevent discharge of material from the hopper 4 when the mold box dies 1 and 2 and the intervening block are displaced beyond the liner 11, 14. Such a means may take the form of a closure plate 40, which may be drawn aside to admit material to the mold box from the hopper, or which may be projected forwardly to cut off communication between the two. The plate is guided at 41, in effect in the fixed frame, to permit such movement to and fro. In the closed or non-communicating position of the closure plate 40 it not only closes the bottom 20 of the hopper, but also the top of the mold box.

In order to receive the block when compressed, and to move it in such manner as to clear the projected mold box parts so that the latter may withdraw for receiving a fresh charge, and in order that this operation may be accomplished with sufficient rapidity, and yet without the likelihood of damaging the compressed but unset block, such as would occur if it were permitted to drop, there is provided a platform or pallet-like arrangement, indicated at 5, which is carried upon a carriage 50 slidably guided at 51 in the frame for substantially vertical movement. The pallet 5 is so positioned that it is directly beneath the projected position of the mold box, that is, the discharging position beyond the edge of the table 30. Means are provided to effect proper and timed movement of the pallet 5 into position to receive and hold the compressed block in situ, and at that moment to open the mold box to release the block, and then to drop the pallet, or otherwise move it with its compressed block out of the way of the mold box parts for return of the latter to charging position.

The description of the controlling mechanism 45 for all the parts so far described has been omitted heretofore, because, for one reason, various mechanisms suited to the ends in view might be designed, and the particular mechanism in the drawings is to be taken primarily as illustrative, although it is operative and practical. Then, too, it is necessary to a thorough understanding of the control mechanism that the general operation and functions of the controlled parts be first understood.

Proceeding, then, to a description of the control mechanism, it will be observed that three cams 6, 7, and 8 are fixed upon a common rotative shaft 31, which shaft is driven through suitable gearing 32 from a drive pulley 33 or other means connected to a suitable power source. The cam 6 reciprocates the yoke 10, and thus effects shifting of the mold box die plates 1 and 2 between the charging and the discharging positions. The cam 7 controls the compressive movement and the reverse relaxing and releasing movements of the die plate 2 relative to the die plate 1, and the cam 8 controls the movement of the closure plate 40. The cam 6, in addition, controls the vertical movement of the pallet 5.

The cam 6 contains a groove 60 within which is received a cam follower roller 61 upon an arm 62 pivoted in the frame at 63 near its lower end, and connected at its upper end at 64 directly to a side arm of the yoke 10. The yoke 20, in addition to being guided at 23 upon the yoke 10, is

joined to the latter to move with the yoke 10 by a toggle-like arrangement, consisting of the links 24 and 25 carrying a roller 26 at their common pivot. The link 24 is pivoted at 26 to the yoke 20, and the link 25 is pivoted at 27 to the yoke 10. Opposed stops 28 and 29, adjustable in a forked end 29 of the link 25, may engage with the yoke 10 to limit the extent of pivotal movement of the link 25, and consequently to limit the relative movement of the yoke 20 with respect to the yoke 10, while not limiting their conjoint movement.

The roller 26 is acted upon by the cam 7, which has both a grooved portion 70 and also an external rise portion 71, and the roller 26 is also acted upon by spaced fixed guides 37, carried by the frame, the purpose of which will appear later.

The cam 8 is a rimmed cam, and a cam follower 81 upon a lever 82, pivoted at 83 in the frame, follows the rim 80 of the cam and effects corresponding movement of the closure plate 40 through a composite rod 42 incorporating a spring 43, which permits the rod to yield in the event the closure plate 40 becomes stuck or encounters an unyielding object such as a piece of gravel.

A cam follower 52 upon a bell crank lever 53, pivoted at 54 in the frame bears upon the outer edge of the cam 6, and transmits motion by way of a link 55, lever 56, and link 57 to the carriage 59, to control its movement. Vertical movement of the carriage is effected in opposition to the cam 6 by a counterweight 58 or the like.

The cam 8 acts primarily to close the closure plate 40, and opening thereof is accomplished by spring mechanism, part of which is illustrated in detail in Figure 3. The head 44 is connected by a rod 45 to the frame, and a similar head 46 is connected by a sleeve 47 to the closure plates 40. The sleeve 47 is slotted for the projection of arms 48, by which the head 44 is connected to the internal, axially disposed rod 45. A compression spring 49 is disposed between the heads 44 and 46. Outward or closing movement of the closure plate 40 causes approach of the head 46 to the fixed head 44, and consequent compression of the spring 49. As soon as is permitted by the cam 8, the force thus stored within the spring 49 effects snap opening of the closure plate 40. The cams time this to occur after the mold box has been returned to the charging position, in registry with the hopper 4.

It will be realized in examining Figures 6, 7 and 8 that, because of the diagrammatic layout, it is necessary to distort certain elements from their proportions and relationship shown in the other figures. However, it is believed that such diagrammatic showings are necessary to make clear the cycle and sequence of operations, since it permits the three cams 6, 7, and 8 to be spread out to be shown in a single plane, though actually they are coaxially aligned in three separate planes.

Figure 5 shows the charging operation. The mold box parts 1 and 2, carried by their respective supporting yokes 10 and 20, are withdrawn to and spread apart within a charging position beneath the throat of the hopper 4, and the closure plate 40 has been opened by expansion of the spring 49. The die plates 1 and 2 are widely separated, because the toggle links 24, 25 are broken to the maximum extent, and the pallet 5 has been withdrawn downwardly, well clear of the level of the mold box, to enable removal of a previously completed block. The cam follower 61, controlling the position of the mold

box has entered an appreciable low dwell 65 of the cam 6. The cam follower 52 is part way through and extended high dwell 66 upon the exterior of cam 6. The cam follower 26, which controls the toggle links 24, 25, has just completed riding along a low dwell 74 of the cam 7. The cam follower 81 is part way through a high dwell 84.

When the requisite charge has been received within the mold box the closure plate 40 is closed and the spring 49 is compressed by the portion 85 of the cam 8, and now, as seen in Figure 6, the cam follower 81 is entering a low dwell 87. This holds the closure plate 40 closed, and the spring 49 compressed. At the same time the cam follower 26 has ridden up the rise 71 of the cam 7 to a dwell 76, the effect of which is to advance the die plate 2 toward the die plate 1 by aligning the toggle links 24, 25. The effect of the approach of the die plate 2 toward the die plate 1 is to compress the charge received within the mold box; and it is of importance in this connection that the compression so accomplished be somewhat in excess of that required to compress the block to its ultimate dimensions, and occur only after closure of the closure plate 40. If, for example, the block is to be six inches high, and is being molded flatwise or on its side, it may be supercompressed to six inches minus thirty thousandths, by the advance of the die plate 2 toward the die plate 1, in the manner indicated in Figure 6.

But there ensues immediately relaxation of the mold box, or separation of the die plates 1 and 2 by an extent sufficient to permit the charge so supercompressed to expand again, but only slightly and uniformly, namely, to the ultimate dimensions of the block. Such relaxation avoids any tendency for the block to swell in the region first uncovered, say by the plate 40, and reverses any such tendency by distributing the expansive tendency throughout the entire block, while it is still confined. Since this relaxation can be accompanied by projection of the mold box toward the discharging position, the relaxation is effected by the action of the cam 77 upon the cam follower 26, tending to and actually slightly breaking the alignment of the toggle links 24 and 25, but at this time the die plates and the mold box as a whole are being advanced or projected outwardly, and so the cam follower 26 is received between the horizontally disposed fixed guides 37 (see Figure 7) which limits the extent of this breaking of the toggle links 24 and 25. Meanwhile the cam follower 61, rising at 67, translates the mold box bodily (minus the liner 11, 14) to the left, or toward the discharging position, for, it will be remembered, the die plate 2 is moved conjointly with the die plate 1 under control of the cam 6, except as the cam 7 causes movement of the die plate 2 relative to the die plate 1. The cam 7, however, does not in any other wise control movement of the die plate 2.

In addition, as the mold box has been moving outwardly toward projected or discharging position, the pallet 5 has been moved upwardly by reason of the cam follower 52 dropping off the high dwell 66 to the low dwell at 68.

At such time as the follower 26 clears the left end of the fixed guide 37, which condition is illustrated in Figure 8, the toggle links 24 and 25 may relax fully, and do so, and effect full release of the block by retracting the die plate 2 relative to the die plate 1. The compressed block would drop upon the pallet 5 when this occurs, were it

not for the fact that this pallet, which previously has been brought into close proximity to the open bottom of the mold box, is just prior to this time moved upwardly the remainder of the way to contact with the lower surface of the block, and to support the block. The means by which this is effected will be explained later, but it is an important part of the process that the block is not permitted to drop when the mold box opens, but is held supported in situ until such time as the mold box is fully opened and the block can be withdrawn from within it, without contact between the block and the mold box, or any part thereof.

Shortly after the pallet 5 has been moved downwardly, that is, after a time sufficient to permit the block to clear the mold box completely, the follower 6 reaches the portion 69' of the cam 6, and the yoke 10, carrying the die plates 1 and 2 in their completely open position, is retracted toward the position of Figure 5. In so doing the cam follower 26 moves below the fixed guides 37 beyond the right hand end thereof, so that parts eventually reach the position of Figure 5. When the mold box has again reached the charging position the cam follower 81 reaches the portion 88 of the cam 8, which permits the spring 49 to expand and quickly to withdraw the closure plate 40, whereupon a fresh charge enters the mold box. Parts are now in the position of Figure 5, and a cycle has been completed. The same cycle can be repeated over and over again.

Upward movement of the pallet 5 under the influence of the weight 58 and as regulated by the cam 6 is limited by a stop 59 on the carriage 50, which may engage a slideable stop 9. This stop 9 is supported upon the frame 3, and is urged to the right, as viewed in Figure 4, by an extension spring 90. It is provided with an upstanding end at 91, which may be engaged by a pin 92 upon the yoke 20, as the latter moves to the left or toward the discharging position. The pin 92 is so positioned with respect to the upstanding end 91 that it engages the latter in the last fraction of the movement of the mold box toward discharging position. Such engagement moves the stop 9 to the left, and permits the stop 59 to rise within the notch 9' of the stop 9, which in turn permits slight upward movement of the pallet 5, and the parts can be arranged with great accuracy so that the pallet 5 will just contact the exposed bottom of the compressed block as the latter reaches its discharging position, and prior to any opening movement or release of the block from the mold box (other than the relaxation already mentioned). Such release immediately ensues, however, and thus the block is left in situ upon the pallet, whereupon the pallet drops to move the compressed block clear of the mold box, and then the latter is retracted, as has already been explained.

The relaxation of the mold box, following compression and prior to release, is an important element of the present invention. Such relaxation need be only a few thousandths of an inch, but is sufficient to permit the entrapped air, which has been compressed, to expand again, but during the supercompression the greater portion of it has been expressed from the block, and only a small portion remains, just sufficient to reexpand the block uniformly throughout to its ultimate dimensions.

The movement of the pallet upwardly into contact with the bottom of the block is likewise of importance in connection with this invention.

This movement may be in the nature of a few thousandths, say thirty-thousandths, of an inch, but thereby the bottom of the block, already compressed, does not have to slide over a fixed pallet, nor yet to drop and risk break-up, nor damage to the necessarily accurate ribs and grooves; the pallet merely contacts the block and holds it where it was while the mold box is stripped or withdrawn sidewise from the compressed block.

We claim as our invention:

1. The process of molding concrete blocks or like products which comprises charging a mold box, compressing such charge therein to less than the intended block size, relaxing such compression 15 to the intended size, maintaining such relaxed compression during a predetermined short interval, and delivering the compressed product from the mold box.

2. Those steps in the compression molding of concrete blocks or like products, which comprise compressing the block to a size less than the intended size, promptly relaxing such compression to the intended size, on at least one side of the block, and during a predetermined short interval, 20 to allow uniform slight expansion of the block during such interval, and removing compression completely on another side of the block at the end of such interval following such expansion of the block, whereby the expanded block may 25 emerge undistorted at its intended size.

3. A machine for molding concrete blocks or like products, comprising a fixed mold box bottom, a charge-conveying chute terminating thereabove, a front and a rear die plate and side plates 35 cooperating with said bottom to form a mold box, said front and rear die plates being guided for conjoint movement between a charge-receiving position, resting upon said mold box bottom and in registry with said chute, and a discharging position beyond said mold box bottom, and being also relatively movable, a block-receiving means at the discharging position, a closure plate 40 for closing the top of said mold box, and movable between a chute-open and a chute-closed position, and control means to effect, in succession, closure of the closure plate to segregate a charge received within the mold box, relative movement of the front and rear die plates to compress such charge, conjoint shifting of the 45 die plates to transfer the mold box to discharging position, separation of the die plates to release the compressed block onto said block-receiving means, and return of parts to the charge-receiving position.

4. The machine defined in claim 3, wherein the block-receiving means comprises a pallet and means supporting and guiding such pallet for movement between lowered position at a level spaced below the fixed mold box bottom by appreciably more than a block's height, and raised 50 position substantially at the level of the fixed mold box bottom, and means operatively connected to the conjoint shifting and die-plate separating means to elevate said pallet to its raised 55 position substantially simultaneously with operation of said means to shift the die-plate into discharging position and to separate the same to release the block, and said means being further operable to depress the pallet into its lowered position immediately thereafter.

5. In a machine for molding precision-interlock concrete blocks or like products, in combination, a mold box formed by complementary top, bottom, two relatively fixed opposite sides and 75 two relatively movable opposite sides, which lat-

fter two sides comprise die-plates shaped and arranged to form complementary precision interlocking block faces, means guiding said die-plate sides for conjoint lateral shifting movement between retracted position interposed between said top and bottom, and projected position disposed beyond said top and bottom, drive means having a definite operating cycle and operatively connected to said die-plate sides to shift the same conjointly, laterally between their retracted and projected positions during succeeding portions of its operating cycle, and die-plate actuating means operatively connected to said drive means for moving said die-plate sides relatively together and apart in controlled sequential manner co-ordinated with such conjoint lateral shifting thereof by said drive means, through a cycle commencing from initially separated charge-receiving position of said die-plate sides while retracted, then relatively together into charge-compressing position while still retracted, then, during a predetermined portion of said operation cycle, very slightly relatively apart, to partially, but not substantially fully, relax block pressure between said die-plate sides, and finally, when said die-plate sides are in projected position, moving them relatively further apart to release the block altogether before subsequent retraction of said die-plate sides again into charge-receiving position between said top and bottom.

16. A machine for molding concrete blocks or like products, comprising a fixed mold box bottom, a charge-conveying chute terminating thereabove, a front and a rear die plate and side plates cooperating with said bottom to form a mold box, said front and rear die plates being guided for conjoint movement between a charge-receiving position, resting upon said mold box bottom and in registry with said chute, and a discharging position beyond said mold box bottom, and being also relatively movable, a block-receiving means at the discharging position, a closure plate for closing the top of said mold box, and movable between a chute-open and a chute-closed position, and control means to effect, in succession, closure of the closure plate to segregate a charge received within the mold box, relative movement of the front and rear die plates to compress such charge, slight reverse relative movement of the front and rear die plates to relax the compression from the maximum previously obtained, conjoint shifting of the die plates in their attained relaxed but still compressed relative positions, to transfer the mold box to discharging position, relative separation of the die plates to release the compressed block onto said block-receiving means, and return of parts to the charge-receiving position.

7. In a machine for molding concrete blocks or like products, a bodily shiftable, open bottom mold box, means to supply a charge thereto, means to close said bottom while it is in charging position, means to compress such charge therein into the form of a block, means to shift said mold box to a delivery position, means to open said mold box at the delivery position to free the compressed block, means at the delivery position to receive and support the freed block, and guided for movement upwardly towards the mold box and downwardly to clear the latter, means controlling movement of said block-receiving means to move the same upwardly towards the open bottom of the mold box as the latter approaches delivery position, said con-

trolling means including a stop upon the block-receiving means and a fixedly positioned but shiftable stepped stop, cooperating to stop the block-receiving means somewhat below the bottom of the mold box, and means carried by and shiftable with the mold box, to engage and shift said stepped stop as the mold box arrives at its delivery position, the stepped stop being arranged relative to its cooperating stop to permit additional upward movement of the block-receiving means into contact with the bottom of the compressed block, said mold box opening means being thereafter operable, and said block-receiving means being thereafter movable downwardly prior to shifting of the mold box.

8. In a machine for molding concrete blocks or like products, a front and a rear die plate and side plates cooperating as parts of a mold box, said front and rear die plates being guided for conjoint movement between a charge-receiving and a discharging station, and also being relatively separable, means interconnecting said die plates for such movements, said means in one position effecting closure of the mold box, and in another position effecting opening thereof for release of the compressed product, means to effect such relative closure movement of the die plates, means to effect conjoint movement of said die plates, means to effect such releasing movement of said die plates, and means operable during conjoint shifting to shift said die plates slightly relatively, and to retain said interconnecting means in an intermediate relaxed position.

9. In a machine for molding concrete blocks or like products, a front and a rear die plate and side plates cooperating as parts of a mold box, further means to complete a closable mold box, said front and rear die plates being guided for conjoint reciprocatory movement between a charge-receiving and a discharging station, and also being relatively reciprocable, a toggle link arrangement operatively interposed between said front and rear die plates to regulate their relative movement, means to shift one die plate, and, through said toggle link connection, also the other die plate conjointly with the first, between the two stations, means to align or to break said toggle links, to compress or to release a charge within the mold box, and means to restrict the extent of breaking of the toggle links, and to retain them in such restricted position, following their compressive alignment and during conjoint shifting prior to opening or to full release of the mold box.

10. The process of molding concrete blocks or like products, of the type having interlocking or critical opposite faces, which comprises charging a mold box, compressing the charge within such mold box to less than the intended block size, relaxing such compression to the intended size by relief of pressure directly against the block's interlocking or critical face during a period to permit expansion of the block substantially to its intended size, and at the end of such period uncovering the block at a non-critical face thereof, to permit the block to emerge undistorted at its intended size.

11. The process of molding concrete blocks or like products, wherein the dimensions of certain faces, less than all its faces, are critical, which comprises charging a mold box; completely closing the mold box; compressing such charge therein to less than its final size; relaxing such compression but only to the extent that the

11

block may expand, by its inherent expansiveness, to the final size in the critical dimensions; while so relaxed opening the mold box along non-critical faces; and thereafter delivering the block from the mold box.

12. A machine for molding concrete blocks or like products, comprising a constrictable mold box having at least two of its opposite sides relatively movable, means operable to charge the mold box, means operable thereafter to complete the closure of the mold box, and mold box actuating mechanism operable to move said opposite sides relatively together and apart, to constrict and relax the mold box, respectively, including power means and cooperating power transfer control means operatively interconnecting said power means and said opposite sides of the mold box, said cooperating power means and power transfer control means having a definite operating cycle and comprising compression means operable during a first phase of said operating cycle to effect movement of said opposite sides, from an initial fully separated position, relatively together to constrict the mold box to a dimension smaller than the intended block dimension between such sides, retraction and holding means operable promptly thereafter, during a second phase of said operating cycle, to move said opposite sides of the mold box relatively apart to relax the mold box substantially to the intended block dimension between such sides, and, during a third phase of said operating cycle, to hold said sides in said mold-box relaxed po-

5

10

15

sition for a predetermined short interval, and further retraction means operable during a succeeding phase of said operating cycle to move said opposite sides further apart for discharge of the block therefrom.

13. The machine defined in claim 12 wherein the relatively movable opposite sides of the mold box correspond to critical faces of the block being molded therein, said machine additionally comprising means coordinated with the power transfer control means and operable in the interval after the second phase and before the fourth phase of the operating cycle of the power transfer control means to open such mold box at a side different from said opposite sides thereof.
